UNITED STATES PATENT OFFICE.

HENRY G. SCHMITT, OF PINE CITY, NEW YORK.

RAILROAD-TIE.

1,365,550.

Specification of Letters Patent. Patented Jan. 11, 1921.

Application filed June 24, 1920. Serial No. 391,321.

To all whom it may concern:

Be it known that I, HENRY G. SCHMITT, a citizen of the United States, residing at Pine City, in the county of Chemung and State of New York, have invented certain new and useful Improvements in Railroad-Ties; and I do declare the following to be a full, clear, and exact description of the invention, such as will enable others skilled in the art to which it appertains to make and use the same.

This invention relates to improvements in railroad ties.

The principal object is to provide a simple and practical railroad tie including a reliable means for retaining rail supporting cushion blocks and their frames in proper position on a base plate.

With the above and other objects in view, the invention consists of certain novel features of construction and the combination and arrangement of parts as will be more fully described and claimed.

I attain these objects by the construction illustrated in the accompanying drawing, in which—

Figure 1, is a side elevation of the tie;

Fig. 2, is a top plan view of the tie;

Fig. 3, is a section on the line 3—3 of

Fig. 2;

Fig. 4, is a top plan view of one box with the block removed.

Fig. 5, is a section on the line 5—5 of Fig. 1;

Fig. 6, is a section on the line 6—6 of Figs. 2 and 3; and

Fig. 7, is a perspective view of the rail fastening plates.

Similar reference numerals designate similar parts throughout the several views.

Reference is now had to the drawings in which the tie is illustrated as comprising an elongated flat metal plate 1, whose central portion 2 is arched to give the tie a slight movement when it is subjected to extreme strain. The end portions 3 of the tie are flat and are each provided with a substantially centrally positioned opening 4 which may be circular or rectangular as preferred.

Disposed at each end of the base plate 1, on the flat end portions 3, is a substantially rectangular metal box 5, the inner end and upper side of which is open as shown in

Fig. 4. Each box is secured to the base plate by rivets or the like fasteners 6 which extend through the bottom of the box and the base plate. In order to insure against shearing off the heads of the rivets or fasteners I form on the box bottom, a lug or boss 7 which is shaped to snugly fit the opening 4 in the base plate. An inwardly extending flange 8 is formed on the upper edge of the closed end of the box to prevent upward movement of the adjacent end of a block 9 to be described. Each box is provided on its two vertical sides with lateral vertically extending wings 10 which are apertured near the upper end to receive tie rods 11 serving to assist in retaining the base plate against extreme bending.

Removably received in each box 5 is a rail supporting and cushioning block 9 which is preferably though not necessarily formed of wood. The block 9 is of a size to fit snugly in the box, and to extend slightly above the upper edge of the box side walls, so that a rail supported on the block will not touch the metal box, but will be cushioned on the block as shown in Fig. 1. The block 9 is insertible into the box from the open inner end and has a portion cut away so that it will snugly fit under the flange 8 at the outer upper end of the box.

A reliable fastening means for each block is provided by taking a metal bar 13 and bending its side edges down to form biting flanges 14 and forming bolt holes adjacent the ends of said bar. The bar is disposed adjacent the inner end of the block with its flanges 14 contacting the block and bolts 15 are then passed through said bolt holes and through suitable openings in the base plate. As shown, the lower ends of the bolts are bent and the upper ends are threaded to receive nuts which are tightened to force the biting edges of the bars into the wooden block.

Rails R will be secured to the blocks by fastening plates 16, each of which is substantially L-shaped, one arm 17 of the plate being slit longitudinally to a point substantially midway the length of the arm. The metal on one side of the slit is adapted to be bent up to form a rail flange engaging portion 18. Lag screws may be employed for securing the plates to the cushion blocks.

Through the construction of these plates, it is readily seen, that when a new rail is to be substituted for an old one, it is only necessary to remove one of the plates to take out 5 the old rail.

From the foregoing description taken in connection with the accompanying drawing, the construction and operation of the invention will be readily understood without requiring a more extended explanation. 10

Various changes in the form, proportion and minor details of construction may be resorted to without departing from the principle or sacrificing any of the advantages of 15 the claimed invention.

I claim:

1. A tie comprising a base plate arched midway its length and having flat end portions, a pair of boxes secured on said flat end 20 portions, said boxes having open inner ends and tops, a pair of rail supporting cushion blocks in said boxes, a pair of cross bars engaging the upper faces of said blocks, and bolts passing through the end portions of 25 said bars and the base plate to secure the blocks in position.

2. A tie comprising a base plate arched

midway its length and having flat end portions, said end portions each having a vertically extending opening therein, a box disposed on each flat end portion, each box having an open inner end and top, a depending lug on each box for snug engagement in one of the openings, rivets connecting the boxes and flat end portions, a pair of rail 30 supporting cushion blocks in said boxes, and means for securing the blocks in said boxes.

3. A tie comprising a base plate arched midway its length and having flat end portions, a pair of boxes having open inner ends 40 and tops, said boxes being secured on the flat end portions, a pair of tie rods connecting said boxes, a pair of rail supporting cushion blocks in said boxes, means for securing said blocks in the boxes, and means 45 for connecting rails with the blocks.

In testimony whereof I have hereunto set my hand in the presence of two subscribing witnesses.

HENRY G. SCHMITT.
